DESIGN FOR A CABINET WATER COOLER

Carter F. Truitt, San Diego, Calif.

Application July 10, 1933. Serial No. 48,679

Term of patent 7 years

To all whom it may concern:

Be it known that I, CARTER F. TRUITT, a citizen of the United States of America, residing at San Diego, in the county of San Diego and State of California, have invented a certain new, original, and ornamental Design for a Cabinet Water Cooler, of which the following is a specification; reference being had to the accompanying drawing forming a part thereof.

Figure 1 is a perspective view of my new design for a cabinet water cooler, and Fig. 2 is a plan view thereof.

I claim:

The ornamental design for a cabinet water cooler, substantially as shown.

In testimony whereof, I have hereunto set my hand at San Diego, California, this 3rd day of June 1933.

CARTER F. TRUITT.
